COVERED FOOD SERVING TABLE

John P. Garneau, Clarion, Pa.

Application March 10, 1959, Serial No. 54,924

Term of patent 14 years

(Cl. D81-12)

Figure 1 is a perspective view of a covered food serving table showing my new design, the side not shown is a substantial duplicate of the side shown,

Figure 2 is an end view thereof. The design is characterized by the rounded top and the scroll-like supporting elements in association with the base, all as shown.

I claim:

The ornamental design for a covered food serving table, as shown, and described.
